BOX CONSTRUCTION

Hubert H. Burke, Chicago, Ill., assignor to The
Package Box Company, a Corporation of
Illinois

Application November 30, 1931
Serial No. 577,911

2 Claims. (Cl. 229—46)

The present invention relates to box constructions, and more particularly to a novel base construction and tying or closure means.

Among the objects of the present invention is to provide a novel reenforced base in box constructions provided with tape, ribbon, string or other tying means whereby to provide a tight closure.

A further object is to provide a base, end or side of a box, with a false bottom adapted to add strength to a construction provided with tying means normally associated with the base.

Another object of the invention is to provide the base, end or side of a box construction with a novel reinforcing member adapted to more evenly distribute the weight of the contents of the box and prevent detachment of the usual base, end or side.

A still further object of the invention is to provide a box or receptacle with a novel tying means including means for positively retaining the tying means in predetermined anchored position.

Another object is the provision of a box or receptacle construction with a strip or strips of tape, ribbon, string or the like, positioned on the interior of a base, side or end thereof, and secured in place for the full extent of their contact with such base, end or side. The present invention contemplates the provision of the tape, ribbon, string or other tying means on the base, end or side wall, and through the adjacent ends or sides of the box or receptacle, and a false bottom stamped or otherwise secured in position over such tying means, whereby to reenforced the base, end or side wall, secure the tying means in position, and cover up the openings through which such tying means pass to the exterior of the box or receptacle so as to provide a weather-tight structure.

Further objects are to provide a construction of maximum simplicity, efficiency, economy and ease of assembly and operation, and such further objects, advantages and capabilities as will later more fully appear and are inherently possessed thereby.

The invention further resides in the combination, construction and arrangement of parts illustrated in the accompanying drawing, and while there is shown therein a preferred embodiment, it is to be understood that the same is susceptible of modification and change, and comprehends other details and constructions, without departing from the spirit of the invention.

In the drawing:

Fig. 1 is a view in perspective of the lower section of the box or receptacle with the tying means in position and the false bottom about to be placed thereover.

Fig. 2 is a view in perspective of the lower surface of the false bottom.

Fig. 3 is a view in vertical cross section through the assembled box or receptacle.

Fig. 4 is a view in perspective of an alternate construction.

Referring more particularly to the disclosure in the drawing, the novel box or receptacle construction comprises a lower section 1 provided with a base or bottom 2, sides 3 and ends 4, and an upper section 5 provided with a top 6, sides 7 and ends 8.

On the interior of the bottom or base 2 of the lower section 1 are provided tying means as tapes, ribbons, strings or the like 9 passing through openings 10 in the side and end walls, and of sufficient length extending exterior of the lower section so as to encompass the sides and ends of the lower section, and the sides, ends and top of the upper section. In order to secure these tapes, ribbons, strings or the like in the lower section and to reinforce the base, the invention comprehends the provision of a false bottom 11 of a size adapted to conformably fit within the box and cover the base, and cover and retain the tying means in position. In order to secure the false bottom and the tying means in position, the lower side of this false bottom is covered with an adhesive, and when the false bottom is stamped or otherwise placed in position, the false bottom, tying means and base will form a substantially integral construction. This provides a greatly reenforced base structure adapted to cover and retain the tying means, cover the openings therefor in the sides and ends of the box or receptacle whereby to form a weather-tight closure, and provide a more even distribution of the weight of the contents of the box or receptacle, thereby to prevent detachment or damage to the base, side and end walls.

In Fig. 4 is disclosed a modification of the base structure suitably adapted for use in small boxes or receptacles which require but one tape, ribbon or string, and which receive articles relatively light in weight. In this form, the lower section 12 of the box comprises a bottom 13, sides 14 and ends 15, with a tape, ribbon, string or tying means 16 positioned on the interior of the bottom 13 and through openings 17 in the side walls 14. In order to secure the tying means in position, and reinforce the bottom adjacent such tying means, the invention comprehends the provision of a strip of

cardboard, heavy paper or other material 18
adapted to completely bridge across the bottom
so as to cover the openings 17. This strip may be
of any width sufficient to satisfy the above re-
quirements. As in the preferred form, adhesive is
5 placed on the lower surface of this strip, so that
when the strip is stamped or otherwise placed in
position, it will be firmly attached to the bottom
or base of the box or receptacle and retain the
10 tape, ribbon, string or other tying means in position.

In the structures disclosed and from the above
description, it will be readily seen that the invention
15 comprehends a novel box or receptacle construction
provided with a reenforced base adapted to
secure and rigidly retain tying means such as
tape, ribbon, string or the like in proper position,
without damage to the box or receptacle structure,
and without danger to the enclosed articles.

20 Having thus disclosed the invention, I claim:

1. In a box, a lower container section comprising
a base and enclosing walls with openings in oppo-
singly disposed walls close to said base and in
25 alignment with each other, a tape resting upon
the inner surface of said base and extended
through said openings, so as to provide tying
means for a cover complementary to said base, and

anchoring means for said tape consisting of a
separate false bottom having a surface area at-
tached to the inner surface of said base, so as to
clamp the tape between them, said false bottom
having edges abutting oppositely disposed walls of
the container section and so positioned within said
container section as to permanently close said
openings with a weather tight seal. 80

2. In a box, a lower container section comprising
a base and enclosing walls, with openings in
oppositely disposed walls close to said base, the
openings in opposite walls being disposed in align-
ment with each other, crossed tapes resting upon
the inner surface of said base and extended
through the respective openings, so as to provide
tying means for a cover complementary to said base,
and anchoring means for said tapes consisting of
a separate false bottom of approximately the same
area as the inner surface of the base, and having
a surface area attached to said inner surface of
the base, so as to clamp the tapes between them,
the marginal edges of said false bottom abutting
contiguous enclosing walls of the container section
and so positioned therein as to permanently close
said openings with a weather tight seal. 85 90 95 100
